UNITED STATES PATENT OFFICE.

GEORGE H. HILL, OF GLENRIDGE, NEW JERSEY, ASSIGNOR TO SPRAGUE ELECTRIC COMPANY, OF NEW YORK, N. Y., A CORPORATION OF NEW JERSEY.

ELECTRIC CONTROLLER.

SPECIFICATION forming part of Letters Patent No. 690,108, dated December 31, 1901.

Application filed August 5, 1901. Serial No. 70,871. (No model.)

To all whom it may concern:

Be it known that I, GEORGE H. HILL, a citizen of the United States, residing at Glenridge, Essex county, New Jersey, have invented certain new and useful Improvements in Electric Controllers, of which the following is a full, clear, and exact description.

My invention relates to electrical controlling apparatus.

10 Among the objects of my invention are simplicity, economy, and durability of construction and ease and effectiveness of operation.

One important feature of my invention is that the controller may be operated from a 15 distance. Although the controller is itself operated by electricity, its use is not confined to electrical apparatus, since it may be used to advantage in connection with apparatus in other arts.

20 In the accompanying drawings I have shown a preferred embodiment of my invention, although it is obvious that the same is susceptible of a variety of modifications.

In the drawings, Figure 1 is a side elevation 25 of my improved controller. Fig. 2 is a front elevation of the same, partly in section. Fig. 3 is a detail sectional view. Figs. 4, 5, and 6 are diagrammatic views of modified forms of circuits which may be employed to 30 operate the controller.

In the drawings, A is a solenoid. B is a plunger adapted to work in said solenoid. The plunger B is preferably hollow.

D is a spring—for example, a coil-spring—35 which may be secured at one end to a suitable anchorage D' and at the other end to the plunger B, preferably in the manner shown. E E' are contacts carried by the plunger B and movable therewith.

40 C C are contact-plates over which the contacts E E' sweep as the plunger moves in or out of the solenoid.

The normal position of the parts is shown in Figs. 1 and 2, in which the solenoid A is 45 practically deenergized and the plunger B and its fittings are in their lowermost position, the spring D being stretched and under its highest operative tension. As soon as the solenoid is energized it elevates the plunger 50 B, thereby contracting the spring D, lessen-

ing the tension therein and the lifting tendency thereof. The lessening of the lifting tendency of the spring D is compensated by the gradually-increased magnetic attractiveness of the solenoid as the plunger projects 55 more and more into said solenoid. As a consequence these two forces tending to elevate the plunger apply a lifting power which is substantially uniform throughout the entire upward excursion of said plunger. 60

By preference a compression-space or air-cushion is provided—for example, within the solenoid—so that the speed of movement of the plunger may be regulated. If desirable, an adjustable air-vent F may be provided for 65 said cushioning-chamber.

B' is a packing which may be provided between the plunger B and the wall of the air-chamber, which packing may also perform the function of a centering means for the 70 proper guidance of said plunger.

In Fig. 4 I have shown a diagrammatic view of one of the systems by which the controller may be operated. In this system, G is a switch. 1 2 are contact-points within the 75 range of the switch G. 3 is a wire leading from the contact 1 to the solenoid. 4 is a resistance located between contact 2 and the wire 3. 5 and 6 are terminals leading from the line-wire to the solenoid A and to the 80 switch G, respectively. 7 and 8 are wires in the motor-circuit. Between the wires 7 and 8 are a succession of resistances 9 9 9, which resistances are connected to the aforesaid contact-plates C C. Any number of these 85 resistances may be cut into or out of the motor-circuit by the contacts E E'.

To operate the controller by the system illustrated in Fig. 4, the operator may throw the switch G from the position shown therein 90 (in which the controller-circuit is open) to contact-point 1, in which position the full value of the current passes through the solenoid, energizing the same and drawing in the plunger B, incidentally cutting out one 95 or more of the motor-circuit resistances 9 9. When the desired number of resistances 9 have been cut in, the operator throws the switch from contact-point 1 to contact-point 2, in which position the resistance 4 is intro- 100

duced into the controller-circuit. The effect of introducing the resistance 4 into the controller-circuit is to reduce the value of the current through the solenoid to an extent sufficient to check and float the plunger at whatever position it happens to be in at that time. The operator may by shifting the switch from the position shown to contact 1, contact 2, or vice versa, raise or lower the plunger B and stop it at any desired point. The position of the plunger may be determined by the operator in any desired way—for example, by a separate mechanical or electrical indicator or by the exercise of judgment and practice.

15 In Fig. 5 another system by which the controller may be operated is shown, in which G' is a switch in the controller-circuit. 11, 12, and 13 are contact-points within the range of the switch G'. 111 121 131 are contact-plates 20 in the controller-circuit. 14 is a resistance between the contact-point 11 and the contact-plate 111. 15 is a resistance between the contact-point 12 and the contact-plate 121. 16 is a resistance between the contact-point 13 and the contact-plate 131. 7 and 8 are wires in the motor-circuit. 9 9 are resistances between the wires 7 and 8, which resistances may be successively cut in or out by the contact E², carried by the plunger. E³ is a contact carried by the plunger and adapted to sweep across the contact-plates 110, 111, 121, and 131. 5 and 6 are terminals leading from the line-wire to the solenoid and the switch G', respectively. In the position shown in Fig. 5 the solenoid is practically deenergized.

To operate the controller by the system illustrated in Fig. 5, the operator may throw the switch G' from the position shown to the contact-point 11, in which position the full value of the current passes through the solenoid, energizing the same, elevating the plunger B until the contact E³ leaves the contact-plate 110 and engages contact-plate 111, whereupon the resistance 14 is introduced. The presence of the resistance 14 in the controller-circuit reduces the value of the current through the solenoid sufficient to check and float the plunger at this point, wherein the said contact E³ engages said contact-plate 111. When the switch G' is moved to cover the contact 11 and 12, the current again flows at its full value through the solenoid, thereby elevating the plunger until the contact E³ leaves the contact-plate 111 and engages contact 121, thus introducing in the controller-circuit the resistance 15, which again reduces the value of the current through the solenoid sufficient to check and float the plunger at a point where the contact E³ will engage said contact-plate 121. To swing the switch G' into such a position that it covers contacts 11, 12, and 13 will cause the current to again flow at its full value through the solenoid, again elevating the plunger until the contact E³ leaves the contact-plate 121 and engages contact-plate 131, in which position it is checked and held by the introduction of resistance 16. It is

obvious that the number of contact-plates and resistances in the controller-circuit may be varied as desired, whereby the number of 70 stopping-points may be correspondingly varied. By the employment of this system for operating the controller the position of the plunger is arbitrarily determined by the position of the switch G'. 75

In Fig. 6 I have shown another system by which the controller may be operated. In this system, G² is a switch. 21 22 23 24 are contact-points within the range of switch G². 25 is a wire leading from contact-point 24 to 80 contact-plate 26. E⁴ is a contact carried by the plunger B or an extension therefrom. 27, 28, 29, and 30 are contact-plates corresponding to contact-plate 26. 31 is a wire leading from the contact E⁴ to the solenoid A. 5 and 6 are wires leading from the line-wire to the solenoid A and to the switch G², respectively. 32 33 are resistances between the contact-points 21, 22, 23, and 24. 34 is a resistance between wire 25 and contact-plate 27. 90 35 is a resistance between contact-plate 27 and contact-plate 28. 36 is a resistance between contact-plates 28 and 29. 37 is a resistance between contact-plates 29 and 30. 7 and 8 are wires in the motor-circuit. 9 9 are resistances between the wires 7 and 8, said resistances having suitable contact-plates which may be bridged by a contact E⁵, carried by the plunger B or an extension therefrom, so that by the position thereof 100 any desired number of resistances 9 may be introduced or cut out of the motor-circuit. The position of the plunger B is determined in this case as follows: The resistances 31 to 37, inclusive, are of equal value and such 105 that when any three or less of them are in series with the solenoid A the value of the current therein will be sufficient to draw in the plunger, thereby elevating the same. The presence of four of the resistances in series 110 with the solenoid will reduce the value of the current to an extent sufficient to check and float the plunger at any given point. The presence of five of the resistances in series 115 with the solenoid will reduce the value of the current passing through the solenoid still further and to an extent sufficient to permit the plunger to drop. With this understanding it is clear that when the switch G² is moved to contact-point 21 the solenoid will 120 be energized and the plunger lifted until the contact E⁴ leaves contact-plate 26 and engages with contact-plate 27, at which elevation it will be checked by reason of the introduction of resistance 34 in addition to the three resistances 31 32 33. If the switch G² is moved from contact 21 to contact 22, the resistance 31 is cut out, leaving only three resistances in series with the solenoid A, whereupon the value of the current therein is sufficient to 125 elevate the plunger, so as to move the contact E⁴ from plate 27 to plate 28, which movement cuts in the fourth resistance 35, at which 130 point the plunger is checked and floated.

Moving the switch G^2 from contact-point 22 to contact-point 23 produces the same effect. The resistance 32 is cut out by the manual act of shifting the switch, and the resistance 36 is introduced by the elevation of the plunger B. The same effect is produced by shifting the switch G from contact-point 23 to contact-point 24, the resistance 33 being cut out by the manual act and the resistance 37 being cut in by the upward movement of the plunger B. In this manner the plunger may be raised step by step to the limit of its upward excursion, or it may be raised by one movement to the limit of its upward excursion by moving the switch from the position shown in Fig. 6 directly to contact-point 24. To lower the plunger B, the switch may be moved from contact-point 24 to contact-point 23, thus momentarily introducing a fifth resistance 33, whereupon the value of the current through solenoid A is reduced to such an extent that the plunger drops, cutting out the resistance 37; but the downward movement of the plunger is checked, so that contact-point E⁴ will remain at plate 29 until the switch G^2 is moved off contact-point 23. The same effect is produced by moving switch G^2 from contact-point 23 to contact-point 22, said movement introducing a fifth resistance 32, which cuts down the value of the current until the plunger shall drop, so as to bring the contact E⁴ into engagement with contact-plate 28. By this system the operator may cause the plunger B to move upward or downward at will, the elevation of the plunger being definitely fixed by the position of the switch G^2 . The position of the plunger B² determines the position of the contact E⁵, and consequently determines the number of resistances in the motor-circuit 78.

Manifestly many modifications may be made in the foregoing systems by which the controller is operated. In fact, it is possible to devise other circuit systems which might be employed with satisfactory results. It should be understood, therefore, that I do not intend to limit that portion of my invention relating, broadly, to the employment of what I choose to term a "floating solenoid" to use with a particular form of circuit system, excepting as certain claims may include specifically the use of said floating solenoid with a particular form of circuit.

As before suggested, the mechanical construction of the controller by which the forces therein are equalized or balanced during the operation of lifting or lowering the plunger is susceptible of a variety of changes. It

should therefore be understood that the substitution of mechanically-equivalent features or variations in the arrangement of the parts to produce substantially the same effect are well within the spirit and scope of my invention.

What I claim is—

1. A controller comprising an electric circuit, a solenoid-magnet, a plunger adapted to coact therewith, means to compensate the variable degree of the magnetic attractiveness of said solenoid to effect a substantial uniformity in the force applied to said plunger in its various positions, and means to vary the value of the current in the solenoid to move or check the plunger at any desired position. 65

2. A controller comprising an electric circuit, a solenoid-magnet, a plunger adapted to coact therewith, means to compensate the variable degree of the magnetic attractiveness of said solenoid to effect a substantial uniformity in the force applied to said plunger in its various positions, and resistance to vary the value of the current in the solenoid to check and float the plunger at any desired position. 75

3. A controller comprising an electric circuit, a solenoid-magnet, a plunger adapted to coact therewith, means to compensate the varying degree of magnetic attractiveness of said solenoid to effect a substantial uniformity in the force applied to said plunger in its various positions, and means to vary the current in the solenoid to move or check one of said parts relatively to the other at any desired position. 85

4. A device of the character described, comprising, an electric circuit, a solenoid-magnet, a plunger, one of said parts being movable relatively to the other, and manually-applied means to check the movement of said part at varying points relatively to the other without interrupting the current through said solenoid. 95

5. A device of the character described comprising, an electric circuit, a solenoid-magnet, a plunger, one of said parts being movable relatively to the other, and manually-applied means to change the value without interrupting the current passing through the solenoid to check one of the parts relatively to the other part. 105 110
